United States Patent

Des. 241,770

Patented Oct. 5, 1976

241,770

COMBINED BELT GUARD AND GUIDE

John W. Davies III, Plymouth, Wis., assignor to
Giesen Brothers Company, Plymouth, Wis.

Filed Aug. 8, 1975, Ser. No. 603,868

Term of patent 14 years

Int. Cl. D15—99

U.S. CL. D15—199

FIG. 1 is a perspective view of a combined belt guard and guide embodying the design.

FIG. 2 is a plan view of the combined belt guard and guide.

FIG. 3 is a side elevation of the right side of the combined belt guard and guide shown in FIG. 2.

FIG. 4 is an end view of the combined belt guard and guide.

I claim:

The ornamental design for a combined belt guard and guide, as shown.
